UNITED STATES PATENT OFFICE.

FREDERICK J. BLOY, OF MILWAUKEE, WISCONSIN.

DESIGN FOR A SAVINGS BANK.

Application filed February 20, 1926. Serial No. 16,599. Term of patent 14 years.

To all whom it may concern:

Be it known that I, FREDERICK J. BLOY, a citizen of the United States, residing at Milwaukee, in the county of Milwaukee and State of Wisconsin, have invented a new, original, and ornamental Design for Savings Bank, of which the following is a specification, reference being had to the accompanying drawings, forming a part thereof.

The figure is a perspective view of a savings bank, showing my new design.

I claim:

The ornamental design for a savings bank, substantially as shown.

In witness whereof, I hereunto subscribe my name this 17th day of February, 1926.

FREDERICK J. BLOY.
